UNITED STATES PATENT OFFICE.

GEORGE R. G. JONES, OF LOUISVILLE, KENTUCKY.

INKSTAND.

SPECIFICATION forming part of Letters Patent No. 402,837, dated May 7, 1889.

Application filed July 31, 1886. Renewed September 6, 1888. Serial No. 284,770. (No model.)

To all whom it may concern:

Be it known that I, GEORGE R. G. JONES, a citizen of the United States, residing at Louisville, in the county of Jefferson and State of Kentucky, have invented certain new and useful Improvements in Inkstands, of which the following is a specification, reference being had therein to the accompanying drawings.

- 10 My invention relates to inkstands, and has for its object the provision of an article which, while combining the advantages of simplicity and durability in construction and cheapness of manufacture, shall also be convenient in 15 operation; and to these ends the invention consists in the construction, combination, and arrangement of parts, substantially as hereinafter fully described, and specifically pointed out in the claims.
- 20 The invention is designed as an improvement on the device shown and claimed in my patent, No. 176,183, dated April 18, 1876.

In the drawings, Figure 1 is a top plan view of my improved inkstand, the cover being adjusted so as to expose but one ink-well. Fig. 2 is a vertical central sectional view, the cover having been placed in its legitimate position. Fig. 3 is a side elevation of the inkstand, and Fig. 4 is an under side view of the cover.

30 Referring to the drawings, A designates the inkstand proper, consisting of a shell, a, of circular form and preferably metallic, and is provided with a supporting-base, a', having a flange, a², which fits inside the lower portion 35 of the shell a.

B designates the top of the stand, having a downwardly-projecting flange, b, which fits within the shell a, and this top plate is provided with three perforations disposed therein 40 at the angles of an equilateral triangle.

In the perforations are placed ink-wells b², which are provided with a cover, C, so formed that any two arms thereof will fit over any two of the wells. This cover C is provided 45 with a knob or handle, c, and around its edge with a downwardly-projecting flange, c'.

The shell a is provided around its exterior with creases a³, preferably four in number, which form in the interior of the shell a series of beads, between which slide endless circular belts or strips D, which are provided at

equal intervals with perforations d, the spaces between the perforations having inscribed thereon the days of the week, month, and year, respectively. The top plate, B, extends outwardly and downwardly a short distance beyond the flanges b all around, except for a small portion, b³, which stands at right angles to the vertical axis of the inkstand and is provided with perforations b⁴, which serves as 60 a pen-rack, the pens being held in an upright position therein. In the side of the shell a are elongated slots a⁴ for the observation of the endless belts or strips D. To adjust the calendar, the strips or endless belts are rotated from notch to notch by turning the same with a pen or pencil.

I do not limit myself to the exact form and construction of parts herein shown and described, but reserve the right to make such 70 modifications and changes in the same as fairly fall within the scope of my invention.

What I claim is—

1. As a new article of manufacture, an inkstand consisting, essentially, of a cylindrical 75 inclosing-shell having a series of angular integral beads on its inner face, formed by indenting or creasing said shell at suitable intervals, and the observation-slots formed between each pair of beads, a series of endless 80 belts, each of which is fitted between two adjoining beads and adapted to be independently turned therein to expose the inscription on its face through one of the observation-slots, and one or more ink-wells suspended 85 within the shell from the cover thereof, substantially as described.

2. As a new article of manufacture, an inkstand consisting of a cylindrical inclosing-shell having a series of annular beads on its 90 inner face, and the observation-slots formed at points between the beads, a series of endless belts, each having its edges fitted between two adjoining beads to be capable of turning therein independently of the other 95 belts of the series, the bottom plate united to the lower open end of the shell, a top plate secured to the upper end of the shell and having an integral perforated flange, b³, and a series of ink-wells suspended within the shell 100 from the top plate thereof, substantially as described.

3. As a new article of manufacture, an ink-stand having a top plate provided with three openings, arranged as described, the ink-wells inserted in said openings, and a cover having
5 three integral sections or members arranged at the angles of an equilateral triangle and each conforming substantially in external contour to the ink-wells, whereby the cover is adapted to be removed bodily from the ink-

wells or to be adjusted over all or any two of 10 the ink-wells, substantially as described.

In testimony whereof I affix my signature in presence of two witnesses.

GEORGE R. G. JONES.
